CLAIM

The ornamental design for a firearm safety lever, as shown and described.

DESCRIPTION

FIG. 1 is an isometric view of a first embodiment of a firearm safety lever, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an isometric view of a second embodiment of a firearm safety lever, showing my new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The dash-dot broken line in the drawings depicts boundary of the claimed design; the evenly broken line in the drawings depicts unclaimed portion of the firearm safety lever only. Broken lines form no part of the claimed design.
